(57) **CLAIM**

The ornamental design of the extendable vehicle decoration, as shown and described.

DESCRIPTION

FIG. 1 is a front, bottom and left side perspective view of the extendable vehicle decoration;

FIG. 2 is a rear, bottom and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a rear, bottom and right side exploded perspective view thereof, with the removable plate exploded off.

In the drawings, the broken lines depict portions of the article that form no part of the claimed design.
